(57) **CLAIM**

The ornamental design for a plumbing control, as shown and described.

DESCRIPTION

In a preferred embodiment, the nature of this product is as a plumbing control in the form of a shower and/or bath control and handle therefor.

FIG. 1 is a left, top, front perspective view of a plumbing control according to our new design;

FIG. 2 is a front elevational view thereof;

FIG. 3 is a left side elevational view thereof, the right side elevational view thereof being a mirror image of the left side shown;

FIG. 4 is a top plan view thereof, the bottom plan view thereof being a mirror image of the top view shown; and,

FIG. 5 is a rear elevational view thereof.

The broken line representations in the figures are for the purpose of illustration only, and form no part of the claimed design.
